JAMES O. H. CAZENOVE, OF NEW YORK, N. Y., ASSIGNOR OF ONE-THIRD TO RAY B. WHITMAN, OF BRIDGEPORT, CONNECTICUT.

OPERATING DEVICE FOR BEATERS.

1,385,605.

Specification of Letters Patent. Patented July 26, 1921.

Application filed February 18, 1920. Serial No. 359,672.

To all whom it may concern:

Be it known that I, JAMES O. H. CAZENOVE, a citizen of the United States, and resident of New York, in the county of 5 New York and State of New York, have invented certain new and useful Improvements in Operating Devices for Beaters, of which the following is a specification.

My invention relates to an improved form 10 of egg beater of the type operable by hand; and an object of my improvement is to provide a beater which will automatically reverse the motion of its beating-blades while the operating handle revolves always in one 15 direction, it having been determined that such reversing motion increases the speed and effectiveness of the beating operation; another object is to accomplish this periodic reversal of motion by using but one driving 20 gear; and a further object is to provide a frame to house suitable bearings for the beater blades, driving wheel, and handle, which can be punched out economically from a single piece of material.

25 I attain these objects by the invention illustrated in the accompanying drawing, in which—

Figure 1 is a side elevation of my complete egg beater; and Fig. 2 is another side 30 elevation of the same, as seen from a plane at right angles to that of Fig. 1.

Similar numerals refer to similar parts throughout the several views.

The frame 1 consists of a strip of flat 35 steel of the shape shown and of suitable thickness, from which a rectangular lip 1^a, Fig. 1, is first punched, leaving thereby an opening 18, Fig. 2. The strip is then bent to the form shown in the drawings, thereby 40 providing at its upper end means for attaching a handle 9, which means consists, for instance, of riveting another flat piece 2 in position shown, and connecting part 2 and upper end or bent section of 1 with a 45 small wire rod surrounded by a coiled spring handle. Or any other suitable form of handle, of course, be substituted. Also, near its middle section, frame-piece 1 is widened out and twisted at right angles to the plane 50 of its upper end portion, so as to provide a housing for the driving-gear bearing; and at its lower end section it is bent substantially as shown, to include two lips, one of them being punched-out lip 1^a, these lips 55 projecting at right angles across the longi-

tudinal axis of the beater, and containing two pairs of holes in alinement to serve as bearings for the axles of the beater blades 13—15 and 14—16.

The driving-gear 3 comprises a hub 3', a 60 circular disk 3 centrally mounted thereon, and a pair of sector plates provided with bevel teeth 4 and 5, respectively, formed on their peripheries; said hub, disk and sector plates all being integrally attached. The 65 bevel teeth on each sector plate face toward the disk 3 but the teeth 4 are positioned on the opposite side of hub 3' to the teeth 5. These teeth 4—5 mesh into beveled-teeth of pinion 10, and are so positioned on driving-gear 3 that the teeth 5 engage the teeth of pinion 10 on one side of said pinion during substantially one-half a revolution of the operating handle 8 which actuates the driving gear 3, through arm 7 riveted at 70 75 to hub 3' and during the other half revolution teeth 4 engage the pinion-teeth at a point on the pinion diametrically opposite the first named point of mesh. By this means pinion 10 with its beater blades 13 80 and 15 positioned at right angles to each other, is caused to revolve periodically in opposite directions, although operating-handle 8 is revolving in but one direction.

Rigidly attached to the shaft which 85 mounts pinion gear 10, and between the two bearing supports of frame 1, as shown, is a small spur gear 11, its teeth meshing into the teeth of a similar-sized spur gear 12, which gear is keyed to the shaft mounting beater 90 blades 14 and 16, which blades are also positioned in planes at right angles to one another, as are blades 13 and 15. In this manner blades 13—15 are caused to revolve always in an opposite direction from blades 95 14—16, the two sets of blades also revolving within each other without interference.

It will thus be seen that my invention discloses a practical means of periodically changing the direction of rotation of the 100 beater blades automatically, and by means of but one driving gear whose teeth are arranged to alternately engage opposite edges of the driving pinion, and, further, that the frame holding the various parts of the completed beater shows a novel construction adapted to economical manufacture.

The operation of my improved egg beater is exactly similar to that of other well-known beaters now universally used, the result only 110

being different in that the blades will rotate three or four times first in one direction, then in the opposite direction, thus much more quickly and effectively accomplishing 5 the desired degree of beating.

I claim:

1. In a device of the class described, the combination of a supporting frame, a hub pivoted in the frame and provided with a 10 handle, a circular disk centrally mounted on the hub, a pair of sector plates provided with bevel teeth on their peripheries and so positioned on opposite sides of the circular disk that the bevel teeth of each sector plate 15 face toward the disk but on opposite sides of the hub, a bevel-tooth pinion journaled in lateral extensions of the frame and disposed to mesh alternately with the bevel teeth of each sector plate, the disk, hub, and 20 plates being all integrally attached, and a pair of spur gears operatively connected to the bevel pinion and mounted in the lateral extensions.

2. In a device for operating beaters, a sup- 25 porting member comprising a sheet metal bar having a vertical portion adapted to support a driving gear, a handle on the upper end of the vertical portion, a lower portion consisting of two horizontal extensions, the

upper of said extensions being pressed out 30 from the body of the vertical portion, a driving gear having diametrically-opposed bevel-tooth sectors and journaled in the vertical portion, a bevel-tooth pinion disposed to mesh alternately with the teeth on each sec- 35 tor, and a pair of spur gears operatively connected with each other and the pinion and journaled in the horizontal extensions.

3. In a device for operating beaters, a sheet metal supporting frame including a 40 pair of arms secured to the ends of a coiled-wire handle, a member integral with one of said arms but twisted to lie in a plane at right angles thereto and perpendicular to the axis of the handle, a pair of lateral ex- 45 tensions formed on the lower end of said member, one of which is pressed out from the body of the member, a driving gear having a central hub carrying two integrally-attached bevel gear sectors and a handle and 50 journaled in the member, a bevel pinion and two spur gears journaled in the lateral extensions and operatively connected to the driving gear.

Signed at New York, in the county of 55 New York and State of New York this 14th day of February, A. D. 1920.

JAS. O. H. CAZENOVE.
